SCREEN DOOR GRILLE

Walter A. Curtze, Erie, Pa.

Application October 3, 1955, Serial No. 38,195

Term of patent 14 years

(Cl. D54—2)

Fig. 1

Fig. 2

Fig. 1 is a front elevational view of the screen door grille showing my new design; and

Fig. 2 is a top edge view.

I claim:

The ornamental design for a screen door grille, substantially as shown.
